UNITED STATES PATENT OFFICE.

WILLIAM LENNON, OF MANITOU, COLORADO.

VAPORIZER FOR INTERNAL-COMBUSTION ENGINES.

1,341,141.

Specification of Letters Patent. Patented May 25, 1920.

Application filed November 22, 1916. Serial No. 132,748.

To all whom it may concern:

Be it known that I, WILLIAM LENNON, a citizen of the United States, residing at Manitou, county of El Paso, and State of Colorado, have invented certain new and useful Improvements in Vaporizers for Internal-Combustion Engines; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for more completely vaporizing the motive fluid or other substances on their way to the intake of the engine and for introducing hot moist air or vapor of water thereto in order to produce a readily ignitable explosive mixture which shall also be of such character that the combustion within the engine cylinders shall be practically perfect, thus avoiding the accumulation of carbon or unburned fuel within the engine cylinders.

In my improvement I arrange a chamber into which the motive fluid or substance is delivered on its way to the intake of the engine, in such a manner that this chamber shall be surrounding or inclosed by a jacket through which the exhaust material or burnt products of combustion pass as they leave the exhaust manifold or pipe. I also provide means for exhausting the air from said jacket when the engine is not running, thus producing a vacuum in the said jacket, which will have a tendency to maintain the heat within the chamber, which condition will facilitate the starting of the engine. Provision is also made for mingling vapor of water with the vaporized motive fluid, the said water being converted into vapor in a small tank or receptacle mounted on the exhaust manifold; and, therefore, kept sufficiently hot to perform the aforesaid function.

Having briefly outlined my improvement, I will proceed to describe the same, reference being made to the accompanying drawing, which is an elevation of an internal combustion engine, equipped with my improvement, the latter being shown partly in section.

In this drawing, let the numeral 5 design-

uate the engine considered in its entirety and equipped with an intake manifold 6; a carbureter 7; and an exhaust manifold 8. A pipe 9 leads from a source of fluid supply (not shown) to the carbureter. This pipe is equipped with a valve 10 whose casing is also in communication with one extremity of a pipe 12, the opposite extremity of said pipe communicating with a small chamber 13 from which also leads a pipe 14 to a mixing chamber 15 which is in communication at one extremity as shown at 16 with the intake manifold, while its opposite extremity is equipped with a closable valve 17 which is pivotally connected as shown at 18 with the inner extremity of a rod 19 whose outer extremity 20 passes through and is movable in the footboard or dash 21 of the automobile. The chamber 13 is surrounded by a jacket 22 which may be filled with any suitable material 23 as sand which will have a tendency to maintain and equalize the temperature within the chamber 13. Surrounding the jacket 22 is another jacket 24 which in reality forms a part of the exhaust manifold, since the products of combustion leaving the exhaust manifold pass through the chamber of jacket 24 and thus heat the chamber 13 and also the jacket 22. Two valves 25 and 26 arranged within the exhaust manifold on opposite sides of the jacket 24, may be closed as indicated in full lines in the drawing. In this event the engine exhausts through an outlet 41. Under these conditions the jacket 24 may be exhausted of its air by connecting the same with an exhauster or air pump of any suitable character. As illustrated in the drawing, a conduit 27 communicates with the jacket 24 at one extremity, while its opposite extremity is in communication with an air pump 28 which is operated from the shaft 29 of the engine through the medium of an operative connection as a belt 30 and pulleys 31 and 32. When the valves 25 and 26 are opened in order to allow the exhaust or products of combustion to escape through the jacket 24, the exhaust outlet 41 will be closed by the valve 24 as indicated by dotted lines in the drawing.

As illustrated in the drawing, the structure is provided with a water receptacle 33 which is in communication by means of a pipe 34 with a receptacle 35 mounted directly on the exhaust manifold 8. The pipe 34 is provided with a controlling valve 36

which is adapted to be manipulated by means of a rod 37 whose rear extremity is accessible to the chauffeur. It should be explained that each of the valve pieces 25 and 5 26, is connected with an operating rod 38, these rods passing through openings formed in the dashboard and being slidable therein. By properly adjusting the valve 36, the water from the tank 33 may be admitted 10 into the receptacle 35 in which it is vaporized by virtue of the heated condition of the receptacle due to its position on the exhaust manifold or pipe. This vapor of water passes through a pipe 39 to the mixing 15 chamber 15 where it mingles with the motive fluid to form a highly combustible explosive mixture, the same being of such character as to be readily ignitable within the engine cylinders and to result in practically perfect combustion.

From the foregoing description the use and operation of my improvement will be readily understood. In the first instance or when starting the machine, the motive fluid 25 passes directly from the supply pipe 9 to the carbureter 7, and this continues until the engine is well started, after which the valve 10 may be adjusted through the medium of a rod 40, to switch the motive fluid from 30 the pipe 9 into the pipe 12, whence it passes into the chamber 13, and thence through the pipe 14 to the mixing chamber 15 where it mingles with the vapor of water which passes to the mixing chamber through the 35 pipe 39 which is in communication with the vaporizing receptacle 35 mounted on the exhaust manifold or pipe as heretofore explained.

By virtue of the fact that the mixing 40 chamber 15 is provided with an open end controlled by the valve 17, it becomes practicable if desirable, to permit the entrance of atmospheric air to the mixing chamber in conjunction and to mingle with the vaporized motive fluid and vapor of water which 45 are introduced to said chamber, as heretofore explained.

Having thus described my invention, what I claim is:

50 1. A device of the class described, comprising a chamber, a jacket surrounding said chamber and carrying a quantity of heat-absorbing material, a second jacket surrounding the first named jacket, the second 55 jacket being mounted on and forming a part of the exhaust conduit and through which the products of combustion from the engine pass, means for closing the exhaust conduit on opposite sides of the second jacket, and 60 means for exhausting the air from the second jacket.

2. A device of the class described, com-

prising a chamber, a jacket surrounding said chamber, a second jacket surrounding the first named jacket, the second jacket 65 being mounted on and forming a part of the exhaust conduit, means for closing the exhaust conduit on opposite sides of the second jacket, and means for exhausting the air from the second jacket. 70

3. A device of the class described, comprising a chamber, a jacket surrounding said chamber, said jacket being a part of the exhaust conduit, means for closing the portion of the exhaust manifold in which the 75 jacket is located, and means for exhausting the closed portion of the exhaust conduit.

4. A vaporizer for internal combustion engines, comprising a chamber mounted adjacent to the exhaust conduit, said chamber 80 being in communication with a source of motive fluid or other supply and also in communication with the engine intake, a jacket surrounding said chamber and forming a part of the exhaust conduit on opposite 85 sides of the jacket, and means for exhausting the air from the jacket.

5. A device of the class described, comprising in combination with an internal combustion engine, a chamber mounted on the 90 exhaust conduit of the engine, said chamber being in communication with a source of motive fluid or other supply and also in communication with the intake of the engine, a jacket surrounding said chamber, said jacket 95 being a part of the exhaust conduit, and through which the products of combustion from the engine pass, valves for closing the exhaust conduit on opposite sides of the said jacket, means for controlling the valves, and 100 means for exhausting the air from the said jacket when the valves are closed.

6. In combination, an internal combustion engine, a carbureter, an intake manifold, an exhaust manifold, a vaporizing 105 chamber mounted adjacent the exhaust manifold, means for introducing fuel to said chamber, said means being in a circuit different from that in which said carbureter is located for introducing fuel to the engine 110 independently of said carbureter, a mixing chamber mounted on and leading into the intake manifold, means for conducting the fuel from the vaporizing chamber to the mixing chamber, and means for introducing 115 water vapor to the mixing chamber, both the chamber and the carbureter being adapted for operation with said fuel.

In testimony whereof I affix my signature, in presence of two witnesses.

WILLIAM LENNON.
